UNITED STATES PATENT OFFICE.

WILLIAM PERSON, OF ROCKFORD, ILLINOIS, ASSIGNOR TO EAST ROCKFORD MANTEL COMPANY, OF ROCKFORD, ILLINOIS.

DESIGN FOR A SEWING-MACHINE CABINET.

SPECIFICATION forming part of Design No. 35,280, dated November 5, 1901.

Application filed September 27, 1901. Serial No. 76,809. Term of patent 3½ years.

To all whom it may concern:

Be it known that I, WILLIAM PERSON, a citizen of the United States, residing at Rockford, in the county of Winnebago and State 5 of Illinois, have invented and produced a new and original Design for Sewing-Machine Cabinets, of which the following is a specification, reference being had to the accompanying drawing, forming part thereof.

10 In the accompanying drawing is shown a perspective view of my design for sewing-machine cabinets.

The design consists in a sewing-machine cabinet substantially of the configuration 15 shown.

The sewing-machine cabinet comprises the top 1, ends 2, and front 3, having the ornamen-

tal design 4. A cover comprises the ends 5, top 6, and curved front 7. A railing 8 is supported by the top and provided with the ornamental design 9.

Having described my invention, what I claim as new, and desire to secure by Letters Patent, is—

The design for a sewing-machine cabinet, 25 substantially as herein shown and described.

In testimony whereof I have signed my name to this specification in presence of two subscribing witnesses.

WILLIAM PERSON.
